HEAVY DUTY LIQUID DETERGENT

Marvin Kopp, Lenox, Mass., assignor to General Aniline & Film Corporation, New York, N.Y., a corporation of Delaware

No Drawing. Application June 11, 1956
Serial No. 590,394

2 Claims. (Cl. 252—152)

The invention here presented is a new, heavy duty detergent, especially suitable for use in automatic washing machines of the tumbling drum type, having a powerful detergent action, suitable for use in relatively substantial quantities and at the same time characterized by the production of a small amount of suds such that the amount is not sufficiently great to overflow the washer when enough is used to obtain the desired heavy duty detergent action; the detergent of the invention being a combination of a nonionic surfactant together with appropriate quantities of carboxymethyl cellulose and an alkanolamine.

For laundering in the tumbling barrel type of washer, especially in the tumbling barrel automatic washers suitable for household use, it is highly desirable that a high power detergent be used, and that it be of such characteristics that it permits of the use of relatively large quantities of detergent. This requires, as a corollary, that the amount of suds produced be relatively small in order to avoid swamping of the detergent effect, and to prevent overflow of suds from the washer; and at the same time it is required that the detergent used shall have a powerful cleansing effect and a minimum tendency to redeposit dirt and soil when it is once loosened from the fabrics being washed. To the present most detergents which are powerful enough for heavy duty service yield so much suds as to muffle the detergent effect, and at the same time to overflow a tumbling barrel type of washer, thereby hampering the detergent effect or limiting the permissible amount used in any given laundering cycle to a quantity so low as to result in inefficient or inadequate cleaning.

According to the present invention it is now found that a nonionic surfactant may be mixed with carboxymethyl cellulose and an alkanolamine such as triethanolamine to produce a heavy duty, liquid detergent which, in action, produces a relatively small amount of suds, such that it may be used in optimum concentration for maximum efficiency of laundering without filling the tumbling barrel and vat so full of suds as to detract from the laundering action, and without danger of filling the washer so full of suds as to cause overflow.

Thus, according to the present invention, there is provided a new composition of matter, characterized by a high power laundering action while producing a relatively small amount of suds, in the form of a mixture of a nonionic surfactant such as the compound resulting from a reaction between a nonylphenol with from 4 to 30 molecules of ethylene oxide in admixture with an appropriate amount of carboxymethyl cellulose and an alkanolamine such as triethanolamine. Other objects and details of the invention will be apparent from the following description.

The primary component of the composition of matter of the present invention is a nonionic surfactant of the type disclosed in U.S. 2,213,477 such as is produced by the reaction between ethylene oxide and an alkylphenol or an aliphatic hydroxy compound such as tridecyl alcohol, lauryl alcohol, etc. as shown in the following equations:

(I)

2

in which R¹ and R² are aliphatic substituents having from 4 to 15 carbon atoms and x is from 3 to 50.

(II) R—O—(CH₂CH₂O)_xH

in which x is preferably 10 but may vary between about 5 and 25, and R is at least 12 carbon atoms, such as disclosed in U.S. 1,970,578.

It will be observed that these compounds are nonionic and a major portion of each is the polymerization product of ethylene oxide.

10 The second component of the composition of the invention is carboxymethyl cellulose which is desirably present in the preparation of 1/4 the amount of the nonionic surfactant but may vary in amount from about 1/15 to about 1/2 of the amount of the nonionic surfactant.

15 The third component of the composition of the invention is an alkanolamine, preferably triethanolamine which is desirably present in the composition in an amount ranging from about 1/3 the amount of the surfactant to an amount of approximately 1 1/2 times the amount of the surfactant, preferably in an amount about equal to the amount of surfactants, these proportions being by weight. A considerable range of alkanolamines may be used for this purpose and they may be either the mono-, di-, or tri- lower alkanolamines, such as

20 (III)

25 in which R is a hydroxyalkyl substituent and R¹ and R² may be hydrogen; alkyl or hydroxyalkyl and the total number of carbon atoms is not over about 13. Thus this component may be a monoethanolamine or may be a mono, di or tri isopropanolamine, or may be monoethanolethylene diamine or monoethanoldiethylenetriamine, or the analogous compounds having such formulas as:

30 (IV)

35 40 in which R¹ and R² have the same meanings as above and R⁴ is a short chain alkylene substituent.

The composition of matter of the invention is then prepared simply by mixing the three components with or without diluting water, and the resulting product is a clear, pourable, stable liquid suitable for packaging or bottling and for shipment as desired. As so prepared, the composition of the invention may contain nonionic detergent, 10 parts to 50 parts by weight carboxymethyl cellulose, 0.01 part to 10 parts by weight alkanolamine, 45 10 parts to 50 parts by weight.

50 In evaluating these mixtures, the procedure used was that shown by Mayhew, Jelinek and Stefcik, as published in the July 1955 issue of the Journal of "Soap and Chemical Specialties."

55 55 The following tests were made upon mixtures prepared as indicated above and they are offered as representative methods which are preferred for the practice of the invention but are not intended to limit the invention in any way.

60 65 In the table there are given 16 examples of specific detergent compositions. Examples 1, 5, 6, 7, 8, 12, 13, 14 and 16 illustrate compositions embraced in the present invention. For comparison therewith, there are given examples of compositions 2, 9 and 15 showing the use of a nonionic surfactant without either triethanolamine or carboxymethyl cellulose; Example 3 showing the effect of water alone; Example 4 showing the composition con-

taining a water-insoluble nonionic surfactant in combination with triethanolamine and carboxymethyl cellulose; Example 10, a composition of a nonionic surfactant and a triethanolamine but containing no carboxymethyl cellulose; Example 11, a composition containing triethanolamine and carboxymethyl cellulose but no nonionic surfactant. In Examples 1, 2, 3 to 10 inclusive, 12, 13 and 16, the nonionic surfactant employed was an alkylphenol condensed with ethylene oxide i.e. a product of the formula

These examples of nonionic surfactant are identified by naming the alkylphenol and the amount of ethylene oxide (sometimes abbreviated in the table as E.O.) condensed therewith. In Compositions 14 and 15 the nonionic surfactant used was the condensate of tridecyl alcohol with ethylene oxide i.e. a product of the formula

10 which is identified by naming the alcohol employed and the amount of ethylene oxide condensed therewith. In the table the number immediately preceding ethylene oxide would be x in the foregoing formulas. In the table triethanolamine is sometimes abbreviated as TEA and carboxymethyl cellulose is abbreviated as CMC.

16	(15% Nonylphenol+9-10 pts. Ethylene Oxide..... 15% Triethanolamine..... 4% CMC..... 66% H ₂ O.....	51.8	36.8	66.2	51.6	82.6	49.0	35.6	64.8	49.8	81.4	1.5	1.5

These results show a detergent efficiency equal to or better than the best commercial detergents, and in addition the products are clear solutions when dissolved in water which do not separate on standing, are not injured by cold, and yield a relatively small amount of suds, such that the detergent effect is not muffled by large quantities of suds, and there is no tendency of suds to overflow the tumbler barrel washing machine.

It will be noted that all of the above formulae involve the use of an alkanolamine such as triethanolamine. A substantial part of the present invention lies in the fact that the presence of the alkanolamine greatly increases the detergent properties of the nonionic surfactants.

Thus the composition of matter of the invention provides a new and useful and highly efficient detergent composition which will form a concentrated aqueous solution resistant to temperature changes, stable on storage and yielding a minor amount of suds while exerting a powerful and potent detergent effect in optimum concentration in wash water.

While there are above disclosed but a limited number of embodiments of the composition of matter of the invention it is possible to provide still other embodiments without departing from the inventive concept herein disclosed, and it is therefore desired that only such limitations be imposed upon the appended claims as are stated therein or required by the prior art.

The invention claimed is:

1. A heavy duty detergent composition consisting essentially of a combination of a water-soluble nonionic surface active agent of the formula

wherein R represents a hydrocarbon radical selected from the group consisting of the hydrocarbon residue of tri-

15 decyl alcohol and nonylphenol and x represents an integer within the range of 9 to 30 with from $\frac{1}{15}$ to $\frac{1}{2}$ by weight of said nonionic surface active agent of carboxymethyl cellulose and from $\frac{1}{3}$ to $1\frac{1}{2}$ times by weight of said nonionic surface active agent of alkanol amine selected from 20 the group consisting of mono, di- and triethanol amine.

2. A heavy duty detergent composition consisting essentially of about equal parts by weight of triethanolamine and a nonionic surface active agent of the formula

together with about $\frac{1}{4}$ the amount by weight of said nonionic surface active agent of carboxymethyl cellulose.
